UNITED STATES PATENT OFFICE.

ROBERT D. BOGUE AND HENRY J. FROMHOLD, OF CINCINNATI, OHIO, ASSIGNEES TO THE CINCINNATI CANDY COMPANY, OF CINCINNATI, OHIO, A CORPORATION OF OHIO.

ART OF DECORATING WRAPPED CANDY.

Application filed April 2, 1927. Serial No. 180,557.

Our invention relates to the art of decorating wrapped candy and includes a combination of steps which relate to the embossing and decorative arts which are carried out in 5 a certain definite series of operations by which the finished decorated wrapped candies may be manufactured.

It is the object of our invention to mold or 10 form candies so that there will be patterns either in an elevated or a depressed plane, to then cover the candies with wrappers which are given the shape of the patterns on the candies and to then decorate the wrappers by the addition of colors or shades which will 15 make the patterns covering parts appear in contrast to the main bodies of the wrappers. It is also our object to proceed with the aforementioned steps in such manner that as much as possible, hand labor may be 20 avoided.

Referring to the drawings in which we have illustrated a piece of candy and a wrapper showing the appearance during the 25 subsequent steps of carrying out our art and process.

Figure 1 is a plan view of a piece of candy shaped as a watch.

Figure 2 is a side elevation of the piece shown in Figure 1.

30 Figure 3 is a plan view of a wrapper for the candy piece.

Figure 4 is a plan view of the wrapped piece prior to the final decorating.

35 Figure 5 is a plan view of the wrapped piece after the final decorating step.

The piece of candy illustrated has a round face portion 1 with raised ordinals 2 indicating the several hours usually indicated on the face of a watch and raised hands 3. The 40 particular candy piece shown also has a stem portion 4 indicated. The wrapper for the piece indicated at 5 is shown as sufficiently large to enclose the entire piece. It will, however, be possible to supply only a sufficient part of the wrapper as would be required to only cover the face of the watch as might be provided with a disc like piece having an area equal to that of the face of the watch.

50 The wrapper is ordinarily of thin material such as foil or tissue and it will be apparent that after wrapping if pressure is brought to bear with a soft roller against the face of

the watch like representation, that the raised ordinals and hands will cause the wrapper 55 to be elevated in the embossed portions. The final step in our process consists in decorating the raised portions of the wrapper which usually consists in passing the wrapped piece into contact with an inking or painting roller. The plane of the surfaces of the ordinals indicated at 6 being slightly elevated from the surface of the watch will cause the ink or paint to adhere thereto without smudging the whole face of 60 the watch. Thus the raised portions of the wrapper may be colored with any desired shade which will contrast with the color of the wrapper.

In carrying out the process in what might 70 be called a reverse manner, the candy piece may have the surface of the dial embossed with the pattern formed with depressions as by a stamping operation. The thin wrapper will then have a surface in one plane and a 75 pattern in an offset plane. In order to decorate such a wrapped piece it will, of course, be necessary to color or decorate the background or surface, leaving the pattern to stand out in contrast to the colored ground. 80

In actual manufacture the wrapped pieces may be passed in a continuous manner under a coloring roller to which paint or ink may be supplied as required. Thus the hand labor of individually decorating each piece 85 may be avoided. A series of wrapped pieces may also be given the original pressing to bring out the embossed pattern of the candy on the wrapper by passing them in a continuous line under a soft rubber roller. 90

In decorating wrapped pieces of candy shaped as watches, it will be possible to use a gold colored foil and to then paint the ordinals with luminous or other paint as indicated at 6^a, which will thus form an object which will find instant appreciation from children because of its similitude to a real watch.

Other types of objects may be molded from candy and embossed patterns in the 100 wrappers for the candy may be similarly decorated as is thought to be apparent.

Having thus described our invention what we claim as new and desire to secure by Letters Patent is:

1. A process of decorating a wrapped

- piece of candy which consists in shaping candy so that a portion to be decorated will have a pattern in raised and depressed portions, wrapping a thin piece of sheet material about the candy, and pressing the sheet against the patterned portion so that it will have raised and elevated portions corresponding with the shape of the pattern in the candy piece, and subsequently coloring the raised portions of the wrapper so that a pattern thereon will appear in contrast to the background.

2. A process of decorating a wrapped piece of candy which consists in shaping candy so that a portion to be decorated will have a pattern in raised and depressed portions, wrapping a thin sheet of material about the candy piece, resiliently pressing the wrapper against the pattern portion, and subsequently applying a coating to the pressed portion of the wrapper.

3. The art of decorating wrapped pieces of candy which consists in the steps of molding a series of pieces of candy with patterns embossed on the faces thereof, wrapping the pieces with thin sheet material, passing the wrapped pieces in a continuous manner under a soft pressing roller, and subsequently passing the pressed pieces into engagement with a coating roller.

4. The process of decorating wrapped pieces of candy which consists in wrapping patterned pieces of candy with thin foil, pressing the wrapped pieces so that the foil will conform to the shape of the candy and subsequently coloring the parts of the foil which lie in substantially the same plane so as to bring out in contrast the pattern of the candy pieces on the wrappers.
